(57) **CLAIM**

The ornamental design for a floater frame, as shown and described.

DESCRIPTION

FIG. 1 is a front perspective view of our new design for a floater frame;

FIG. 2 is a front elevation view of the design of FIG. 1; FIG. 3 is a rear elevation view of the design of FIG. 1; FIG. 4 is a top plan view of the design of FIG. 1; the bottom view being identical;

FIG. 5 is a cross-sectional view, taken along and in the direction of line 5-5 in FIG. 2;

FIG. 6 is a left side view of the design of FIG. 1, the right side view being identical; and,

FIG. 7 is a front perspective view of the design of FIG. 1, illustrating the design of FIG. 1 with an unclaimed canvas mounted in the frame as environment.

The floater frame is shown with symbolic breaks. The appearance of any portion of the article between the break lines forms no part of the claimed design.

The dot-dash-dot broken lines depict the boundaries of the floater frame and form no part of the claimed design. The broken lines in the corners of the floater frame illustrate portions of the article that form no part of the claimed design. All other broken lines depict environmental subject matter that forms no part of the claimed design.
